REGENERATING SCINTILLATION COUNTER

Joseph Lempert, Elmira, N.Y., assignor to Westinghouse Electric Corporation, East Pittsburgh, Pa., a corporation of Pennsylvania

Application November 26, 1954, Serial No. 471,330

10 Claims. (Cl. 250—213)

My invention relates to radiation detectors and in particular to a regenerative form of radiation detector which is of greater sensitivity than radiation detectors of the prior art. It also includes a novel type of radiation image intensifier and is also applicable to a novel type of current pulse generator.

Radiation detectors have been proposed in which radiation quanta incident on a suitable phosphor or other fluorescent material generate light which strikes a photoelectric cell and causes current flow in the output circuit thereof. In accordance with one feature of my invention a more sensitive radiation detecting device is attained by forming the photoelectric cathode as a thin layer parallel and closely spaced from the fluorescent layer, for example by superimposing the two layers on opposite sides of the thin glass wall of an electronic tube, and bombarding an electron phosphor output screen in the tube with the photoelectrons generated at the surface of the photoelectric layer. The light flash produced in this way at the output phosphor by each radiation quantum striking the input phosphor is of many times the energy of the latter, and relatively weak incident radiation may be thus detected. Moreover, where the input radiation is in the form of an image field, both the electron stream and the light field generated on the output screen may be made to reproduce the space distribution of the image field, and the device thus produces an intensified light image of the input radiation field. By making the space between the photo electric layer and the output phosphor very small, and using as the electron phosphor a material which emits light predominantly of a wave length to which the photoelectric layer is copiously responsive, the light emitted back toward the photoelectric layer when its electrons strike the electron phosphor acts regeneratively on the former to generate additional electrons which will, in turn, be accelerated into contact with corresponding portions of the electron phosphor output screen and increase the luminosity of the latter still further. By this regenerative action, the sensitivity of the apparatus to the input radiation is greatly increased.

If the electrons projected from the photoelectric surface can be compelled to traverse paths normal to the screen surface, and the light projected backward from the electron phosphor output surface could be confined to similar normal paths, the distribution of light intensity in the output image would correspond exactly to the distribution of intensity of the input radiation, and the light image on the output screen would be an exact replica of the input radiation field. Scattering of electrons from such normal paths may be effectively prevented by providing a magnetic field normal to the screens; and the effects of both electron scattering and light-ray scattering may be minimized by making the distance between the photoelectric surface and the electron phosphor surface small. Furthermore, scattering of the back-reflected light may be minimized by providing a grid of thin polished metal strips forming a kind of honeycomb of fine-bore light tunnels between the electron phosphor and photo-

2

electric surfaces which confine the backward-emitted light rays to paths along these light-tunnels to the photo electric surface.

When using the tube of my invention as a radiation detector, the regenerative properties I have described would cause a continued buildup of output light and of electron flow which could persist even after termination of the initiating radiation pulse unless provision were made to terminate this buildup. The buildup may be terminated, for example, by allowing the electron flow through the photoelectric screen to charge a capacitor in the grid circuit of a tube controlling the voltage supply to the output of the radiation detector and thereby interrupting further operation of the detector until another photon of radiation being detected strikes the input screen.

The electron flow from the photoelectric screen would build up in successive steps due to the above described regenerative action; viz, a given incident photon would cause emission of a definite number of electrons immediately following its incidence; after these had had time to travel to the electron phosphor screen they would generate light, and as soon as the latter traveled back to the photoelectric screen a second burst of electrons would be added to the electron stream. The length of this interval between inception of the first and second electron pulses from the photoelectric screen could be given any desired value by properly fixing the voltage and spacing between the photoelectric screen and the electron phosphor screen; and by arranging a capacitor circuit in a well-known way to cut off current flow after occurrence of a predetermined number of such pulses, a novel type of pulse generator is obtained.

One object of my invention is accordingly to provide a novel and more sensitive type of radiation detector.

Another object is to provide a novel circuit for radiation detectors making use of a regenerative combination of photoelectric screens and electron phosphor screens.

Another object is to provide a novel type of periodic electrical pulse generator.

Another object is to provide a novel and improved type of radiation image reproducer.

Another object is to provide a novel and improved type of radiation field transformer.

Another object is to provide a new type of light or other radiation image intensifier.

Yet another object is to provide a novel arrangement for improving the resolution and preventing blurring of the images in picture reproducing tubes which utilize combinations of photoelectric and electron phosphor screens.

Other objects of my invention will become apparent to those skilled in the electronic art upon reading the following description taken in connection with the drawings in which the figure is a schematic view in perspective of a tube in accordance with my invention which may be employed either as a radiation detector or as a radiation image reproducer.

Referring in detail to the drawings, a radiation detector and image transforming tube embodying the principles of my invention may comprise a vacuum-tight enclosure 1 of glass having a pair of flat parallel side walls, one of these bearing on its outer surface a layer or input screen 2 of material which the radiation to be detected causes to emit light or other radiation. For example, if the radiation to be detected is X-rays the layer 2 may comprise zinc sulphide. The side wall bearing layer 2 should be as thin as is practicable and should have its inner face coated with a thin layer 3 of a material which emits electrons copiously in response to the radiation emitted by layer 2; for example, where layer 2 is of zinc sulphide the layer 3 may be of cesiated antimony. A lead-in 4 sealed through the wall of container 1 allows current flow from external circuits to layer 3. Parallel

to photoelectric layer 3, and spaced away from it by the minimum distance affording insulation against the voltage impressed between them, is an output layer or screen 5 which may, if desired, be supported on the opposite side wall of container 1 and which comprises an electron phosphor which preferably emits light or other radiation to which layer 3 is photoelectrically responsive. To give one instance, layer 5 may be $ZnSiO_4:Mn$ or $Zn_2SiO_4:Si$. A lead-in 6 makes it possible to impress voltage on output screen 5.

While operability of this tube is not dependent upon its presence, performance as a transformer or reproducer of input radiation images will be better if the space between layers 3 and 5 is occupied by a grid or honeycomb 7 of thin polished sheet-metal strips forming light ducts or tunnels normal to output screen 5 and having diameters small relative to their lengths so that light generated by impact of electrons at screen 5 is prevented from scattering laterally from a path normal to that screen in traveling toward photoelectric layer 3. The honeycomb 7 is provided with a lead-in 8 by which its potential may be fixed at will relative to photoelectric layer 3. If the potential of the honeycomb 7 is made sufficiently positive to layer 3, secondary emission may be attained of such magnitude as to amplify the electron stream by secondary emission.

The lead-in 4 for photoelectric layer 3 is connected through a pulse counter 11, of any known type capable of registering the number of pulses of electric current passing through it, to the negative pole of a direct-current voltage source 12 having its positive pole connected through a resistor 13 and an inductance 14 to the anode of a grid-controlled electron tube 15. The cathode of tube 15 is connected through the lead-in 6 to output screen 5. A direct-current bias source 16 makes it possible to impress a desirable bias between honeycomb 7 and photoelectric layer 3. A capacitor 17 shunted by bleeder-resistor 18 is connected through a pair of blocking capacitors 19 across the resistor 13; and the terminals of capacitor 17 are connected to the control electrode and cathode of tube 15 so that, as charge accumulates on the capacitor when current flows through tube 15, the control electrode of the latter becomes increasingly negative relative to its cathode and alternately blocks current flow therein. Any other blocking tube circuit known in the art as suitable to block current flow after passage of a predetermined charge may replace this tube 15 circuit, however.

The above-described circuit may be used as a radiation detector in the following way. The radiation to be detected is projected onto the input layer 2 where each photon generator projects light from its point of impact, through the wall of enclosure 1, and onto the adjacent small area of photoelectric layer 3. Electrons are emitted from the opposite face of this small area and are attracted by the electric field due to the positive potential impressed by voltage source 12 through control tube 15 on output screen 5. The electrons from the above-mentioned small area pass through the particular tunnel or duct of honeycomb 7 which overlies that area, and are thus compelled to move in paths normal to photoelectric screen 3 and prevented from scattering laterally to other portions of output screen 5.

Upon striking output screen 5, the electrons generate light, part of which is projected forward to points outside tube 1, and part of which is projected backward, through the above-mentioned light duct in honeycomb 7, onto the same small area of photoelectric screen 3 in which the electrons originated. The light duct in honeycomb 7 has thus prevented any scattering of either electrons or the returning light from the particular small area of the input screen on which the original radiation photon was incident.

The light returned to photoelectric layer 3 causes the emission therefrom of an additional burst of electrons

which are attracted through the same light duct of honeycomb 7 into incidence with the same area of output screen 8; there they emit more light to points outside tube 1 and return more light to photoelectric screen 3 where they generate a third burst of electrons. This cumulative buildup by successive steps of electron flow from photoelectric screen 3 and of light emission from output screen 5, at the small area corresponding to the point on the input screen where the detected radiation photon was incident would continue indefinitely, and long after such incidence, were this regenerative action not terminated by some means, such as interruption of the impression of voltage output on screen 5 through control tube 15. To effect such an interruption of the regenerative action resistor 13, which is traversed by the current corresponding to electron flow between photoelectric screen 3 and output screen 5, is shunted by capacitor 17 so that the latter acquires a charge corresponding to each burst of electrons passing through the duct of honeycomb 7. Capacitor 17 is so connected to the cathode and control grid of control tube 15 as to impress a negative bias thereon which grows greater with each successive cumulative step in the buildup of the electron flow to output screen 5. This step-by-step increase of the negative bias tends to terminate current flow through control tube 15, but is opposed for a time by the self-inductance of inductance 14. Soon, however, the current through tube 15 sinks to zero, the effectiveness of inductance 14 expires, and the acquired negative charge on capacitor 17 keeps control tube 15 nonconductive until that charge leaks away through bleeder-resistor 18. After an interval fixed by the time constant of capacitor 17 and resistor 18, control tube 15 becomes conductive again, and the system can react as described above to the incidence of a new photon of the detected radiation on input screen 2.

To obtain proper operation of this apparatus as a radiation detector and photon counter, the time period of the capacitor 17-resistor 18 circuit must be less than the time intervals between incident photons of the detected radiation, as must also be the decay-period of the phosphors in screens 2 and 5. The pulse counter 11 will then register each pulse of current built up through control tube 15 and so register the number of photons incident on input screen 2.

The time between successive steps in the buildup of current produced by each incident photon is the time required by an electron to traverse the distance between photoelectric screen 3 and output screen 5 plus the time required for light to return to screen 3 over the same distance, the latter time being usually negligible compared with the former, and being adjustable by varying the voltage impressed by source 12. The circuit may thus be considered as a means for generating stepped current pulses of predetermined period, and comprising on each pulse a number of steps regulated by properly adjusting the time-constant of the capacitor 17-resistor 18 circuit.

Since the honeycomb 7 insures that the illumination produced on output screen 5 is confined to a small area corresponding in position to that one which the incident photon of the detected radiation strikes, a space-distributed field of detected photons will produce a light-emission on output screen 5 which is a replica in distribution of that field; in other words, my arrangement will transform the input radiation field into an output radiation field from screen 5, which is its replica or image. Thus, for example, a picture will appear on output screen 5 of an X-ray image which was projected onto input screen 2; and its intensity may be many fold that of the X-ray image, being determined by energy drawn from the local voltage source 12. In short, the tube 1 acts as an image intensifier.

The surfaces of the light ducts in honeycomb 7 may be coated with cesiated antimony or other secondary electron emitter to increase the efficiency of this por-

tion of tube 1. In such case the potential of honeycomb 7 should be sufficiently positive relative to layer 3 to be above the first crossover in the voltage vs. secondary emission curve well known in the radio art. However, provided the distance between layers 3 and 5 is made of the order of the areas in the image field which it is desired to resolve optically, the arrangement is operative as a picture reproducer even though honeycomb 7 is omitted. A spacing of half a millimeter will suffice for many images. It may be noted that cesiated antimony is also a good photoelectric emitter and that light waves radiated by the output screen back into the honeycomb cells will augment the electron stream. Silver magnesium (AgMg) is also a good cell-lining material.

When it is desired merely to reproduce and intensify a light image the input screen 2 may be omitted and the light image be focussed on the photoelectric screen 3.

In reproducing image fields on the output layer 5, it is of course necessary that the electron density at different points over the area of screen 5 shall correspond to the light-intensity at corresponding areas of input screen 3. If the regenerative action described above for radiation detector operation is employed in the apparatus and allowed to continue too long, it will build up to the point where the electron-emitting power of the portion of screen 3 within each of every honeycomb cell will reach saturation so that further increase of emission is impossible, and all contrast of brightness between different areas of the output screen be destroyed. Hence the control tube 15 must be adjusted to interrupt the impression of voltage on screen 16 before saturation conditions are reached even in the brightest areas of the picture.

I claim as my invention:

1. A radiation responsive device comprising a vacuum-tight enclosure, a first screen therein responsive to emit electrons upon incidence of a photon of input radiation thereon, a second screen therein responsive to incidence of electrons to emit an output radiation to which said first screen is photoelectrically responsive, a honeycomb structure of ducts positioned between and normal to said first and second screens, and a circuit connecting said first screen to said second screen and responsive to the amount of current flow and containing means to interrupt current flow after passage of a predetermined amount of current.

2. A radiation responsive device comprising a vacuum-tight enclosure, a first screen therein responsive to emit electrons upon incidence of a photon of input radiation thereon, a second screen therein responsive to incidence of electrons to emit an output radiation to which said first screen is photoelectrically responsive, said first and second screens being spaced apart by a distance of the order of resolution required in pictures, and a circuit connecting said first screen to said second screen which is responsive to the amount of current flow and containing means to interrupt current flow after passage of a predetermined amount of current.

3. A radiation responsive device comprising a vacuum-tight enclosure, a first screen therein responsive to emit electrons upon incidence of a photon of input radiation thereon, a second screen therein responsive to incidence of electrons to emit an output radiation to which said first screen is photoelectrically responsive, a honeycomb structure of ducts positioned between and normal to said first and second screens, and a circuit connecting said first screen to said second screen and containing means to interrupt current flow therein upon passage of a predetermined quantity of electricity, and a pulse counting device in said circuit.

4. A radiation responsive device comprising a vacuum-tight enclosure, a first screen therein responsive to emit electrons upon incidence of a photon of input radiation thereon, a second screen therein responsive to incidence of electrons to emit an output radiation to which said first screen is photoelectrically responsive, and a circuit

connecting said first screen to said second screen and containing means to interrupt current flow therein, and a pulse counting device in said circuit.

5. A radiation responsive device comprising a vacuum-tight enclosure, a first screen therein responsive to emit electrons upon incidence of a photon of input radiation thereon, a second screen therein responsive to incidence of electrons to emit an output radiation to which said first screen is photoelectrically responsive, and a circuit connecting said first screen to said second screen and containing means to interrupt current flow therein upon passage of a predetermined quantity of electricity.

6. A radiation responsive device comprising a vacuum-tight enclosure, a first screen therein responsive to the incidence of a photon of input radiation thereon and emitting electrons in response to said input radiation, a second screen therein responsive to incidence of electrons to emit an output radiation to which said first screen is photoelectrically responsive, a honeycomb structure of ducts positioned between and normal to said first and second screens, the internal faces of said ducts exhibiting the property of reflecting said output radiation and circuit means connecting said first screen to said second screen and responsive to the amount of current flow and containing means to interrupt current flow after passage of a predetermined amount of current.

7. A radiation responsive device comprising a vacuum-tight enclosure, a first screen therein responsive to the incidence of a photon of input radiation thereon to cause emission of electrons therefrom, a second screen therein responsive to incidence of electrons to emit an output radiation to which said first screen is photoelectrically responsive, a honeycomb structure of ducts positioned between and normal to said first and second screens, said ducts having surfaces which freely emit secondary electrons and a circuit connecting said first screen to said second screen and containing means to interrupt current flow therein upon passage of a predetermined quantity of electricity.

8. A radiation responsive device comprising a vacuum-tight enclosure, a first screen therein responsive to the incidence of a photon of input radiation thereon to cause emission of electrons, a second screen therein responsive to incidence of electrons to emit an output radiation to which said first screen is photoelectrically responsive, a honeycomb structure of ducts positioned between and normal to said first and second screens, said ducts having surfaces which are photoelectrically emissive and a circuit connecting said first screen to said second screen and containing means to interrupt current flow therein upon passage of a predetermined quantity of electricity.

9. A radiation responsive device comprising a vacuum-tight enclosure, a first screen therein responsive to the incidence of a photon of input radiation thereon to cause emission of electrons therefrom, a second screen therein responsive to incidence of electrons to emit an output radiation to which said first screen is photoelectrically responsive, a honeycomb structure of ducts positioned between and normal to said first and second screens, said ducts are coated with cesiated antimony and circuit means connecting said first screen to said second screen and containing means to interrupt current flow therein upon passage of a predetermined quantity of electricity.

10. A radiation responsive device comprising a vacuum-tight enclosure, a first screen therein responsive to the incidence of a photon of input radiation thereon to cause generation of electrons, a second screen therein responsive to incidence of electrons to emit an output radiation to which said first screen is photoelectrically responsive, a honeycomb structure of ducts positioned between and normal to said first and second screens, said ducts having surfaces which freely emit secondary electrons, and circuit means connecting said first and second screens to accelerate electrons emitted from said first screen and the

surface of said ducts into incidence with said second screen.
